UNITED STATES PATENT OFFICE.

JACOB SKEEN, OF ALLEGHENY, PENNSYLVANIA.

IMPROVEMENT IN WAGON STANDARDS AND BOLSTERS.

Specification forming part of Letters Patent No. 155,987, dated October 13, 1874; application filed February 7, 1874.

To all whom it may concern:

Be it known that I, JACOB SKEEN, of Allegheny, in the county of Allegheny and State of Pennsylvania, have invented a new and useful Improvement in Wagon-Bolsters and their attachments; and I do hereby declare that the following is a full and exact description of the same, reference being had to the accompanying drawings, and to the letters of reference marked thereon.

The object I have in view is such an improvement in the construction of bolsters and their stakes and locking-keys, for use in wagons, as will add to their convenience in use, and to their durability and cheapness; and my invention therein consists in the novel construction of the bolsters, the stakes, and their locking-keys.

In order to enable those skilled in the art to construct my bolster and attachments, I proceed to describe the same in connection with the drawings, in which—

Figure 1 is a side elevation of one of the bolsters, with the stakes in position; Fig. 2, a top view of one of the bolsters without the stakes; Figs. 3, 4, 5, and 6, separate views of the stakes; Figs. 7 and 8, separate views of the keys.

Like letters designate corresponding parts in each figure.

A represents the bolster, of any convenient size or form, having at its ends, upon its upper surface, plates B, properly secured thereto. In these plates is a rectangular opening, a, for the reception of the foot of the stake, which opening extends down through the bolster. Between this opening and the ends of the bolster are circular openings b for the reception of a holding-stud upon the stakes. Upon the bottom of the bolster, is another plate, C, having openings c to correspond with the openings a just named, and upon the sides of the bolsters are other plates, D, placed opposite to each other, and having key-holes d of the general form of a key-hole for a common lock, or circular key-holes d', to suit the different sorts of keys hereinafter described. These plates are all preferably sunk into the bolster to a level with its surface. Upon these bolsters the stakes E E¹ E² E³ are intended to be placed, their feet fitting in the openings a, and pass-

ing down through the bolsters, and the upper and lower plates before named. In each of these stakes there is a recess, e, upon each side of their tops, leaving the metal very thin between them; and in the offsetting-stakes E¹ there are other recesses, e¹, upon each side of the shoulders f, or offsetting parts; and there may, if desired, also be other recesses, e², upon each side of the feet. There are also upon each of the stakes, upon each side, wings e³, arranged centrally with their bases upon the same plane as their seats, which rest upon the tops of the bolsters. Of these stakes, that designated by the letter E has a straight body, f¹, the lower part of which rests upon the bolsters, and is there furnished with a stud, f², intended to fit into the opening b in the top plate of the bolster. The foot f³ of this stake is offset, as shown in Fig. 5, and has a central opening, f⁴, which is circular, and provided with screw-threads for one kind of key, and has an ordinary carpet-bag key-hole form, f⁵, for the other kind of key. The stake E¹ differs from that described in having its body curved outwardly, as shown in Fig. 4. The stake E² differs from those already described in being straight from top to bottom, having no offset or shoulder; and the stake E³ differs from this last in having its body curved outwardly, neither of these stakes having the stud f². The keys F F' are of two sorts, each having on one side a handle, g, bending downward to serve as a weight to hold it in position, a shoulder, g¹, to limit its penetration through the bolster, and a body, g². In the key F this body, about midway, is diminished in size throughout the outer part, and that portion next to the part so diminished in size is provided with screw-threads. In the key F' the body is of the same size throughout, and at the extreme end has a small fin, g³, upon the same side with the handle, which gives it the form of an ordinary carpet-bag key.

In securing the stakes in position the key F is used like a screw, and its threaded part engages with the threaded round opening in the stake, and binds it firmly in place, the weighted handle hanging down preventing it from turning or unscrewing.

The key F' is entered through the key-holes in the plates and stakes, and so as to lock its

fin over its proper plate, in which position it is held by the weight of its down-hanging handle.

The bolster-plates are made of iron plates, cut and perforated by suitable shears and dies. The stakes and the keys described are preferably made of cast metal, either composed of steel or of malleable iron, or what is now known as converted steel.

The advantages of my improvement are so apparent upon inspection as to require no particular mention.

Having thus explained my improvements, what I claim as new therein, and my own invention, is—

1. The bolster A, the plates B, C, and D, having openings a, c, and d d', all constructed

and combined substantially as described and shown.

2. The stakes E E¹ E² E³, having recesses upon their sides and side wings, substantially as described and shown.

3. The keys F F', in combination with the stakes, substantially as described and shown.

4. The bolster A, having the plates B, C, and D, in combination with the stakes E E¹ E² E³, all substantially as described and shown.

This specification signed and witnessed this 3d day of February, 1874.

JACOB SKEEN.
